UNITED STATES PATENT OFFICE

2,497,104

MULTIPLE GAS BURNER

William R. Vandiver, Tulsa, Okla.

Application February 21, 1946, Serial No. 649,210

2 Claims. (Cl. 158—104)

1

My invention relates to gas burners and more particularly to burners using natural gas.

The object of my invention is to provide a gas burner constructed practically entirely of pipes of different sizes and plates, making it possible to construct burners of any desired size by using larger or smaller pipes.

Other objects of my invention may appear in the following specification, describing my invention with reference to the accompanying drawing illustrating a preferred embodiment of my invention. It is, however, to be understood that my invention is not to be limited or restricted to the exact construction and combination of parts described in the specification and shown in the drawing, but that such changes and modifications can be made which fall in the scope of the claims appended hereto.

In the drawing:

Figure 1 is a top view of the burner according to my invention partly shown in section, and

Figure 2 is a sectional view taken on line 2—2 in Figure 1.

Referring now to the drawing in detail the burner according to my invention has a circular bottom plate 10 resting on foot brackets 11. In the center of this plate a pipe 12 is arranged extending through a hole in the bottom plate and fastened thereon so that a gastight seam is obtained, for instance, by welding. A pipe 13 is welded to the bottom plate 10 and also welded thereon to form a gastight connection. The diameter of the plate 10 equals the outside diameter of the pipe 13.

Diametrically opposite to each other two other pipes 14 and 15 extend through holes in the bottom plate 10 and are welded thereto to form gas-tight seams. They are located at equal distances from the center pipe 12.

A pipe 16 surrounds the center pipe 12 and is welded concentrically therewith to the bottom plate 10, forming a gastight connection with this plate and extending upwardly therefrom.

A ring shaped baffle plate 17 is connected rigidly and gastight with the upper end of the pipe 16. The center hole in the ring shaped baffle plate 17 has the same diameter as the inside of the pipe 16. At its outer circumference the baffle plate 17 extends beyond the outside pipe 13 and the pipe 16 is somewhat longer than the outside pipe so that an opening is formed between the ring shaped baffle plate 17 and the top edge of the outside pipe 13.

A pipe 18 is connected gastight with the ring shaped baffle plate 17 and extends downwardly therefrom. It is arranged so that it is concentric with the pipe 16, which forms an inner wall for the outer mixing chamber 19 of the gas burner of my invention, and it is spaced an equal distance from the vertical gas duct pipe 14

as the inner wall pipe. The pipe 18 forms a deflecting wall for the outer mixing chamber 19, extends down to the bottom plate 10 and is provided with a plurality of holes 20 therein adjacent said bottom plate.

An inner deflecting pipe 21 is fastened to the bottom plate 10 and surrounds the gas duct pipe 12 concentrically therewith. It is arranged approximately halfway between the inner wall pipe 16 and center gas duct 12. It extends upwardly beyond the ring shaped baffle plate 17 and a circular baffle plate 22 is fastened gastight to its top and extends with its circumference beyond the inner wall pipe 16. A plurality of openings 23 are provided in the deflecting pipe 21 adjacent the bottom plate 10.

A main gas duct 24, which is connected with a source of natural gas (not shown), is supported by the foot brackets 11 and extends diametrically underneath the circular bottom plate 10 directly under the gas duct pipes 14, 12 and 15. It forms the gas manifold and has an opening 25 directly under each of said gas duct pipes.

When gas is admitted into the manifold 24 it will flow out of the holes 25 into the gas duct pipes 12, 14 and 15. The gas in the ducts 14 and 15 hits the ring shaped baffle plate 17 and flows downwardly through the outer mixing chamber 19 as indicated by the arrows in said chamber. Thereby the gas will be mixed thoroughly with air and this mixture flows through the holes 20 in the deflecting pipe 18 into the space between this pipe and the outer pipe 13, which it will leave through the opening between the top edge of the outer pipe and the baffle ring 17. Ignited, it forms an outer flame of intense heat.

Gas flowing upwardly through the center gas duct 12 is deflected by the baffle 22 and the inner deflecting pipe 21 to flow downwardly. Thereby this gas is thoroughly mixed with air. It flows through the openings 23 in the deflecting pipe 21 into the space between this pipe and the inner wall pipe 16. Flowing upwardly in this space it leaves the burner through the space between the circular baffle 22 and the ring baffle 17 ready to be ignited and to form the inner flame of the burner.

The above described burner produces a perfect mixture of gas and air insuring perfect combustion and producing an exceedingly hot flame.

Having described my invention what I claim and desire to secure by Letters Patent, is:

1. A gas burner having a gas manifold connected with a source of gas and provided with a plurality of outlet openings, and an inner and outer concentric aerating chamber, said burner including a circular bottom plate, a plurality of brackets supporting the bottom plate and the manifold, the manifold extending diametrically

underneath the bottom plate, a pipe sealed to the bottom plate and extending upwardly therefrom and forming the outer wall of the burner, a second pipe sealed to the bottom plate concentric to the outside wall inwardly thereof and forming the inner wall of the outer and the outer wall of the inner aerating chambers, an annular baffle plate sealed to the top of said second pipe, said second pipe being longer than said first pipe, the marginal edge of said baffle extending radially beyond said first pipe, a gas duct pipe arranged over each outlet opening in said manifold and extending upwardly through said bottom plate, a deflecting wall pipe fastened onto the bottom plate inside said second pipe and concentric thereto, a plurality of openings in said deflecting wall pipe adjacent said bottom plate, said deflecting wall pipe being longer than said second pipe, a baffle disc sealed to the top of said deflecting wall pipe, the marginal edge of said disc extending radially beyond said second pipe, an outer deflecting wall pipe arranged inside said first pipe intermediate the same and said second pipe and concentric with all of said pipes, said outer deflecting wall pipe being sealed to said annular baffle and extending downwardly to said bottom plate, a plurality of holes in said outer deflecting wall pipe adjacent said bottom plate, one of the gas duct pipes leading into the space inside said inner deflecting wall pipe and the other gas duct pipes leading into the space between said second wall pipe and said outer deflecting wall pipe.

2. A gas burner, comprising means forming at least two concentric aerating chambers, a common floor for both of said chambers, a substantially cylindrical vertical outer wall for one chamber, a substantially cylindrical inner wall for said one chamber, said inner wall being concentric to said first wall and inwardly spaced

therefrom, said second wall extending substantially above said first wall and defining the outer wall of the other of said chambers, a flat plate arranged about the extending end of said second wall and secured thereto, a substantially cylindrical baffle positioned in said one chamber and spaced inwardly from one wall of the chamber and outwardly of the other, said baffle having the end adjacent said floor provided with openings extending therethrough and having the other end secured to said flat plate, a second substantially cylindrical baffle positioned in said other chamber and spaced inwardly from the outer wall of the latter chamber, said second-named baffle having the end adjacent said floor provided with openings extending therethrough and having the other end extending substantially above the outer wall of said other chamber, a second flat plate positioned upon the extending end of said second-named baffle and closing the latter end, said second-named flat plate extending outwardly from said second-named baffle, and means for admitting gas and air to each of said chambers inwardly of said baffles.

25 WILLIAM R. VANDIVER.
